UNITED STATES PATENT OFFICE

MORRIS VICTORSOHN, OF BROOKLYN, NEW YORK

HANGER SUPPORT

Application filed October 4, 1929. Serial No. 397,292.

The subject-matter of the present invention relates generally to apparel apparatus, but specifically has to do with improvements in supports adapted for placement in a container, such as a trunk, suitcase, traveling bag, or the like, to receive hangers for carrying wearing apparel.

Primarily, the object of the invention resides in the provision of a novel form of support adapted to support a plurality of hangers, or a single hanger, as desired.

Another object is to provide means whereby the usual pintles of the garment hanger are substantially imprisoned or maintained in such association therewith as to preclude the accidental displacement of said hangers during the portage or handling of the container.

A further object of the invention is to provide an article of the above-mentioned character which may be formed from a single piece of metallic material and which is inherently resilient to permit of placement of the hanger therein and the removal of the hanger therefrom, said article being fashioned or manufactured with a minimum of operations, thus materially reducing the cost of production.

As will presently appear the invention is 30 featured with resilient means which slightly resist the insertion of the pintles of a hanger and which cooperates with a housing or hooded portion to prevent the escape of the pintles when the container assumes various positions.

A still further object is to provide means in the form of projections or indentations which support the pintles at various positions within the structure of the device and 40 which permit the passage of the pintles thereover in view of the resiliency of said device.

With these objects in view, together with others which will appear as the description proceeds, the invention resides in the novel formation, combination, and arrangement of parts, all as will be described more fully hereinafter, illustrated in the drawings, and particularly pointed out in the claims.

50 In said drawings:

Figure 1 is an elevation of my improved hanger support mounted within a container and carrying a hanger in one position.

Fig. 2 is an end elevation of a single support as viewed in the direction of the arrow, 55 the pintle of a hanger being sectioned on line 2-2 and showing it supported on oppositely disposed indentations or projections.

Fig. 3 is also an end elevation showing 60 the end opposite to that shown in Fig. 2.

Fig. 4 is a rear elevation of the article.

Fig. 5 is a transverse sectional view taken on the line 5-5 of Fig. 2.

Fig. 6 is a perspective view of the upper 65 portion of the article.

Referring now more in particular to the accompanying drawings, wherein like characters of reference denote similar parts throughout the several views, let 5 denote 70 generally a container, which may be in the form of a trunk, or similar article-carrying device, and having a rear wall 6 and side walls 7 and 8. It will, of course, be understood that the showing of a container is 75 merely illustrative and not to be considered restrictive in any sense.

As shown in Fig. 1, of the drawings, two of the supports will be secured within the container 5, preferably abutting the rear 80 wall 6 thereof and spaced to accommodate the type of hangers used. The supports shown are identical and hence a detailed description of one will suffice.

The supports, designated by the numeral 85 9, are each formed from a single piece of material which is bent and cut away to present the finished article shown in the drawings, which includes a flange portion 10, suitably apertured as indicated at 11, 90 for the reception of fastening means 12, whereby the article is secured to the container, as aforesaid. The material is then given a series of right-angular bends to present walls 13, 14, 15 and 16 (see Fig. 5), the lower end of said wall 16 being bent inwardly to present a base 17, as shown in Fig. 2. The upper portion of said wall 16 is also bent inwardly to define a top 18, 95 and then downwardly a short distance, as 100

shown at 19, the lower edge thereof being spaced above the top edge of wall 14 to define a notch 20, as shown in Figs. 2 and 4. To complete the structure said flange portion 10 is cut to present an upwardly directed resilient tongue 21, which is bowed inwardly toward the part 19 and spaced therefrom a distance slightly less than the diameter of the pintles 22 of the hanger 23. Finally, suitable projections or indentations 24 and 25 and struck-in from the walls 14 and 16, each pair being oppositely disposed, as shown, and spaced apart a distance slightly less than the diameter of the pintles. From the foregoing it is apparent that the bending of the walls 14 and 16, as aforesaid, provides a housing for the pintle, which is closed at the top and bottom, and also the sides with the exception of the open front portion and the notch 20.

With the supports secured in the position hereinbefore mentioned, a hanger may be inserted therein by first pressing the pintles between the tongue 21 and part 19, the resiliency of the former permitting the passage of said pintle, and as it comes opposite the notch 20, it is passed therethrough and then downwardly through the housing, or between the walls 14 and 16, until it abuts the projections 24. Here it rests and the hanger will thus be supported with the pintle 22 abutting said projections 24, as clearly shown in Fig. 2. As the walls 14 and 16 are resilient, said pintle may be gently forced between said projections 24 and passed downwardly until it abuts projections 25, and finally this operation may be continued until the pintle rests on the bottom 17. In the removal of the hanger, the pintle may be operated in the reverse to that just described until it is freed from the tongue 21. If a container is inverted from normal position, the pintles may slide within the housing, but cannot escape therefrom, as some will contact the projections, where the uppermost one will engage the top 18. If, by chance, a pintle should pass through the notch 20, it is retained by the cooperation between tongue 21 and part 19. The article is exceedingly simple in construction and admirably adapted for the purpose aforesaid.

While the present is a disclosure of the preferred embodiment of the invention, it is to be understood that the invention is not limited thereto, as various changes in the minor details of construction, proportion and arrangement of parts may be resorted to without departing from the spirit of the invention as defined in the appended claims.

I claim:

1. A device of the character described adapted to be secured within a container to support a pintle of a hanger, and having a housing portion including side walls, one

of the side walls having its upper portion bent inwardly to define a top for the housing and being bent downwardly in the plane of the other side wall and having its lower edge spaced above the top edge of the latter to present a notch, and a resilient tongue spaced from said notch and adapted to be flexed to permit the insertion of the pintle in the notch for passage within said housing, the said top of the housing serving to prevent the escape of the pintle when the container is inverted from normal position.

2. In a device of the character described, a support adapted to be secured within a container to support a pintle of a hanger, and having a housing portion including side walls and a bottom, one of the side walls presenting a notch, and having oppositely disposed projections, and a resilient tongue spaced from said notch and adapted to be flexed to permit the insertion of the pintle in the notch for passage within said housing to abut said projections.

3. In a device of the character described, a support adapted to be secured within a container to support a pintle of a hanger, and having a housing portion having an open front portion and resilient side walls, one of said walls presenting a notch, a plurality of oppositely disposed projections extending inwardly from said side walls and a resilient tongue spaced from said notch and adapted to be flexed to permit the insertion of the pintle in the notch for passage within said housing, said resilient side walls permitting the passage of the pintle between a pair of oppositely disposed projections.

In testimony whereof I affix my signature.

MORRIS VICTORSOHN.
